UNITED STATES PATENT OFFICE.

RICHARD B. CHARLTON, OF MILWAUKEE, WISCONSIN, ASSIGNOR TO THE
CONTINUOUS RAIL JOINT COMPANY OF AMERICA, A CORPORATION OF
NEW JERSEY.

MEANS FOR FORMING FISH-PLATES.

SPECIFICATION forming part of Letters Patent No. 699,148, dated May 6, 1902.

Application filed August 10, 1901. Serial No. 71,611. (No model.)

To all whom it may concern:

Be it known that I, RICHARD B. CHARLTON, a citizen of the United States, residing at Milwaukee, in the county of Milwaukee and State 5 of Wisconsin, have invented certain new and useful Improvements in Means for Forming Fish-Plates; and I do hereby declare the following to be a full, clear, and exact description of the invention, such as will enable others to skilled in the art to which it appertains to make and use the same, reference being had to the accompanying drawings, and to letters of reference marked thereon, which form a part of this specification.

15 This invention relates to the manufacture of that form of fish-plate shown in my prior patents, Nos. 667,499, 667,500, and 667,501, issued February 5, 1901; and the objects of the present invention are to facilitate the formation 20 of the upturned girder or truss of the fish-plate; to enable the entire operation of rolling the fish-plate bars, cutting them into lengths, bending up the girder, and punching, slotting, &c., the fish-plate to be done at 25 a single or initial heat to thus avoid repeatedly heating and working the metal to the detriment of the finished product, and to secure other advantages and results, some of which may be referred to hereinafter in connection 30 with the description of the working parts.

The invention consists in the improved means for forming fish-plates and in the arrangements and combinations of parts of the 35 same, all substantially as will be hereinafter set forth and finally embraced in the clauses of the claim.

Referring to the accompanying drawings, in which like letters of reference indicate corresponding parts in each of the several figures, Figures 1 and 2 show my improved apparatus in plan. Fig. 3 is a perspective view of the girder-bending dies, and Fig. 4 shows the means by which the fish-plates are supplied to the said bending-dies. Figs. 5 and 45 6 show in perspective the punching and slotting dies, respectively.

In said drawings, *a a* indicate rolls forming the final or finishing pass of a set adapted to 50 roll bars of suitable cross-sectional form from

which to cut fish-plates, and *b* is such a bar emerging from said rolls. Said bar then passes upon rollers *c* or any other common form of conveyer under a cutting-off saw *d*, of the pendulum type and located at a convenient distance from the rolls, which severs the bar into pieces of the lengths desired for fish-plates. To determine this length, a gage or stop *e* is provided, normally lying below the plane of the upper surfaces of the conveying- 55 rollers *c* and adapted to be elevated, as by the rock-shaft *e'* and hand-lever *e''*. Beyond the saw *d* the sawed-off lengths *b'* of the bar are delivered by the conveyer-rollers *c* to other conveying-rollers *f*, which have inclined or 60 conical surfaces adapted to give the fish-plate a quarter-turn at the same time it is carried forward. This insures that the fish-plate, which has been sawed as delivered from the rolls *a a*, with its side which is in use to lie 65 against the rail turned downward, is now re-adjusted with said contact side in vertical position and the base member *i* turned uppermost. When thus turned by the rollers *f*, the 70 fish-plate is carried in that position by rollers *j* and delivered to the girder-forming dies. Said dies comprise a stationary female member *g*, lying at one side of the path of the fish-plate, and a reciprocating male member *h*, adapted to be slid transversely of the path- 75 way of the fish-plate toward and away from the female member *g*. Both members are mounted upon a suitable bed *k*, and the male member *h* is given motion by the crank *k'*, receiving power from any suitable source. The 80 female member *g* consists of a block of metal facing that side of the fish-plate which becomes the outside in use and having a recess or groove *g'* to admit the toe member *l* and doubled or V-shaped portion of the fish-plate. 85 Above said groove or recess the overhanging portion of the block is cut away at its central portion, as at *g''*, to expose the base member of the fish-plate. The male die member is at 90 its front face shaped to conform to and fit against the contact or bearing side of the plate, with an extension *h'* to enter the V-shaped portion thereof. Upon the upper surface of said extension *h'* and conforming in longitudinal 95 position with recess *g''* of the female die is a 100

projection h^2 , adapted to enter said recess g^2 when the die members are forced together and press the exposed portion of the base member i up into a girder m . The fish-plates then fall 5 onto a table n , as shown in Fig. 3. From said table the fish-plates are caught with tongs and placed one at a time first in a punch o , which makes the bolt-holes in the upright portion of the plate, and then in a 10 slotter p , which makes slots p' in the toe-flange to receive the spikes by which the fish-plate is to be fastened to the ties. The finished fish-plates b^3 are then loaded on a tram-car q or the like to be taken away.

15 It will be noted that the described operation of bending up the girders m is performed in the same heat with the rolling of the bar, sawing it into lengths, and punching and slotting. This is effected by means of the rapid 20 automatic handling of the hot plates and not only saves time and labor, but also secures a better product, in that repeated heating and reworking is avoided.

Having thus described the invention, what 25 I claim as new is—

1. The herein-described dies g , h , for forming girders m , on fish-plates, comprising a female die having at one lateral face a recess or groove g' , to receive a fish-plate, the upper 30 overhanging edge of the die being cut away at its middle portion, and a male die h , adapted to fit at its lateral face against a fish-plate as it lies in the female member, and having a projection h^2 , to enter the recess in 35 upper edge of said female member.

2. The herein-described means for forming an upright girder on the base member of fish-plates having an upright portion and doubled base, comprising a fixed die member grooved

at its lateral face to receive the doubled base 40 of the fish-plate and having a portion of its face at one side of said groove cut away to expose the base member of the fish-plate, and a reciprocating male die member having a 45 face adapted to fit against a fish-plate as it lies in the female die member and having a projection to enter the cut-away portion thereof and bend up the exposed base member of the fish-plate.

3. The combination with the fixed die member g , having in its lateral face a groove g' , for holding a fish-plate in inverted position and a recess g^2 , exposing the base member of said fish-plate, a movable member h , having a projection h^2 , adapted to enter said recess 50 g^2 , and bend up the exposed portion of the base member, and means for automatically supplying fish-plates in said inverted position.

4. The combination with means for delivering fish-plates of the character described each with its base in vertical position, of conveyer-rollers f , adapted to give a fish-plate a quarter-turn, while carrying it forward, and bring its base uppermost, and bending-dies 65 adapted to receive between themselves a fish-plate in said position, and having one a recess exposing the base member and the other a projection adapted to enter said recess and bend up the exposed portion of said base member.

In testimony that I claim the foregoing I have hereunto set my hand this 31st day of July, 1901.

RICHARD B. CHARLTON.
